UNITED STATES PATENT OFFICE.

FREEMAN N. YOUNG AND FRANCIS E. THOMPSON, OF ARLINGTON,
MASSACHUSETTS.

ADVERTISING-REFRIGERATOR.

SPECIFICATION forming part of Letters Patent No. 641,917, dated January 23, 1900.

Application filed June 28, 1899. Serial No. 722,171. (No model.)

To all whom it may concern:

Be it known that we, FREEMAN N. YOUNG and FRANCIS E. THOMPSON, citizens of the United States, residing at Arlington, in the county of Middlesex and State of Massachusetts, have invented certain new and useful Improvements in Advertising-Refrigerators, of which the following is a full, clear, and exact description.

10 This invention is an advertising-refrigerator, the advertising feature of the refrigerator being due to its shape. The apparatus is intended to be used in the business of retailing a certain beverage by the glass. The 15 beverage is put up in bottles of a certain shape and is more palatable when kept on ice. For the purpose of thus keeping the beverage and at the same time of advertising it we propose to make a refrigerator in the form of a 20 bottle in which the beverage is sold, but of sufficiently large dimensions to contain a quantity of ice, a number of bottles of the beverage, and, if desired, a number of drinking-glasses in which the beverage is sold to customers. The intention is to place this refrigerator upon shop-counters, at proper locations 25 upon the street, or at any other desired place where it will be in plain sight of the public and where it may be in the care of an attendant who will dispense the beverage.

The apparatus is illustrated in the accompanying drawings, in which—

Figure 1 is a perspective view of the refrigerator; Fig. 2, a vertical section thereof, and Fig. 3 a horizontal section.

As above stated, the refrigerator is in the form of a bottle of large dimensions. The body portion A is preferably of papier-mâché or some other light and impervious material 40 adapted to hold ice and water, the body being hollow for this purpose. The upper portion of the body is tapered into a neck b, closed at the top by a suitable cap b', the whole structure—body, neck, and cap—being 45 of the same shape and proportions as a bottle in which a certain beverage is sold, the particular beverage intended to be used in this instance being "moxie." For advertising purposes one side of the bottle, which we will 50 call the "front," will be provided with a la-

bel, which is a facsimile of the label used on moxie-bottles. The bottle may also contain any other advertising words or matter. In the back of the bottle one or more doors c will be formed, through which access to the 55 interior may be had, and near the bottom a spigot d will be placed to draw off the water. It is intended to place a quantity of broken ice inside and to plunge into it a number of bottles of the beverage named.

60

The refrigerator is preferably made in two parts, the joint occurring in a horizontal plane at the point where the body commences to narrow into the neck. The neck portion will preferably be removable in order to quickly 65 charge the body portion with ice and the bottles of beverage and also for the purpose of cleaning the interior.

The drinking-glasses in which the beverage is sold should be kept cool, and for this purpose we have arranged in the neck portion of the refrigerator a rack e, provided with a number of hooks, on which the glasses or mugs may be suspended. The neck portion may be removed from the refrigerator and 70 placed upon the ground or other support without removing the glasses, since they will be held above the lower edge. When the parts are assembled and the refrigerator is equipped for dispensing the beverage, the 75 glasses can be easily reached through the doors c in the same way that the bottles of liquid are reached. The bottles containing the beverage (moxie) are sealed by a well-known kind of metal cap, an imitation of 80 which is shown at b', and for removing this cap it is customary to use a small lever having a ring at one end adapted to fit over the cap and engage its edge, whereupon the cap can be lifted. For convenience we have shown 85 such a ring f permanently attached to the exterior of the refrigerator. By thrusting the top of the bottle into this ring and engaging the cap the latter may be easily removed.

As it is the intention to distribute these 90 refrigerators among retail dealers in beverages, it is the intention to prevent its use as a water-cooler or a tank for lemonade or other drinks in bulk by coating the inner walls with a paint or material which will give an objec- 100

tionable flavor to any liquid placed in the refrigerator in bulk. Hence it can only be used to contain liquids or materials contained in other packages, such as the bottles described.

The refrigerator may be lined with a harmless preparation containing sassafras or any other strong-flavored material solvent in water which will impart an unusual taste to the water.

Having described our invention, we claim—

1. An advertising-refrigerator consisting of a box or casing in the form of a bottle, the body portion having a door or doors and 15 adapted to contain ice and material to be kept cool, and the neck portion being separable from the body portion and provided with

racks for supporting glasses, substantially as described.

2. An advertising-refrigerator consisting of 20 a box or casing in the form of a bottle provided with a door or doors in its side, and with a spigot for drawing off the loose liquid contents, the inner walls of the casing being coated with a material capable of imparting 25 an obnoxious taste to any liquid contained in the refrigerator.

In witness whereof we subscribe our signatures in presence of two witnesses.

FREEMAN N. YOUNG.
FRANCIS E. THOMPSON.
